UNITED STATES PATENT OFFICE

2,088,600

POSITION COMPARATOR

James C. Karnes, Buffalo, N. Y.

Application November 9, 1934, Serial No. 752,365

2 Claims. (Cl. 116—124)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a position comparator. In pointing control systems for ordnance, searchlights, sound locators and similarly mounted members it is customary to ascertain and compute the necessary pointing data at a remote 10 station and transmit it to the gun which is moved until a rotatably mounted pointer controlled by the gun is matched or compared with a rotatably mounted pointer controlled from the remote data station. The application of such 15 pointer systems to the gun has resulted in a cumbersome arrangement which interferes with other equipment and with the operating crew.

The purpose of this invention is to provide a 20 position comparator whose elements may be conveniently and compactly associated with the training mechanism of the gun. A further object is to provide reference marks on a pair of parallel slides whereby under conditions of darkness registration of the marks may be determined 25 by the sense of touch.

To these and other ends, the invention consists in the construction, arrangement and combination of elements described hereinafter and pointed out in the claims forming a part of this 30 specification.

A practical embodiment of the invention is illustrated in the accompanying drawing, wherein:

Fig. 1 is a view in left side elevation of a 35 gun showing the improved comparator in association with the elevating mechanism.

Fig. 2 is a view in rear elevation.

Fig. 3 is a similar view in right side elevation of the gun showing a comparator in association 40 with the traversing mechanism.

Referring to the drawing by characters of reference there is shown a mount comprising a base 5, a pedestal 6 rotatably carried by the base on a vertical pivot 7, and a cradle 8 rotatably carried by the pedestal on horizontal trunnions 9—9. A gun 10 or other device is carried by the cradle.

The mount is provided with conventional training mechanisms for moving the gun in azimuth and in elevation. Briefly, the base 5 carries a fixed ring gear 11 which is engaged by a pinion 12 on a shaft 13 that is mounted on the pedestal 6. A worm wheel 14 on the shaft is driven by a worm 15 on a shaft 16 to which is fixed the traversing handwheel 17. The cradle 8 has the usual arc 18 which is engaged by a pinion 19 on a shaft 20 carrying an elevating handwheel 21.

60 A rack 22 provided with a reference mark 23

and slidably mounted in a guide 24 on the pedestal is driven by a pinion 25 on the shaft 13 and its displacement represents the motion of the traversing mechanism or the position of the gun in azimuth. Similarly a rack 26 provided 5 with a reference mark 27 and mounted in a guide 28 on the opposite side of the pedestal is driven by the elevating mechanism, specifically by a gear 29 associated with one of the trunnions 9, and its displacement represents the motion of 10 the elevating mechanism or the position of the gun in elevation.

A rack 30 having a reference mark 31 is mounted alongside the rack 22 and a rack 32 having a reference mark 33 is similarly mounted with 15 relation to the rack 26. The racks 30 and 32 are displaced to indicate, with or without corrections, the position of an instrument or instruments at a remote station, by means of self-synchronous electrical systems for transmitting 20 angular motion. The receiving motors 34 and 35 of the systems are positioned within the pedestal 6 and carry pinions 36 and 37 respectively meshing with the racks 30 and 32.

In operation, when the racks 30 and 32 are 25 displaced by the motors, the handwheels 17 and 21 are actuated by the gun crew a sufficient amount to maintain the reference marks on the racks 22 and 26 in register with the reference marks on the racks 30 and 32. Under conditions of darkness the operator at each handwheel may determine registration of the marks by placing a finger at the ends of the racks to feel if they are flush. When the reference marks are in 30 register the gun will have been positioned in 35 accordance with the position of the instrument at the remote station.

I claim.

1. A pedestal mounted for movement in azimuth, means for traversing the pedestal, a pointing member trunnioned in the pedestal, means for elevating the pointing member, a pair of first indicators carried on the outside of the pedestal and displaceable to respectively represent the position of the pointing member in azimuth and elevation, a pair of means housed within the pedestal for reproducing azimuth and elevation data, and a pair of second indicators arranged on the outside of the pedestal for comparison with the first indicators and respectively 40 actuated by the reproducing means.

2. In a position comparator, a rotatable member, a slide, means whereby the rotatable member controls displacement of the slide, a second 45 slide arranged adjacent to and comparable with the preceding slide, and a rotatable reproducing member controlling displacement of the second slide.

JAMES C. KARNES. 60
